COVER FOR MILK BOTTLE CARRIER

Robert A. Bruce, 1256 15th St., Koesauqua, Iowa

Filed Mar. 21, 1960, Ser. No. 60,001

Term of patent 14 years

(Cl. D58—5)

Fig. 1

I claim:

The ornamental design for a cover for a milk bottle carrier, substantially as shown and described.
